OIL COOLER

John Ralph Holmes, Lockport, N. Y., assignor to
General Motors Corporation, Detroit, Mich., a
corporation of Delaware

Application April 7, 1934, Serial No. 719,611

6 Claims. (Cl. 257—236)

This invention relates to heat exchangers, and particularly to oil coolers which are capable of handling and efficiently cooling large quantities of oil in short periods of time.

5 To cool large quantities of oil in short periods of time, it has been considered necessary to employ large and bulky pieces of apparatus. It is an object of this invention to provide a relatively small and compact oil cooler which is capable 10 of cooling a large quantity of oil in a short period of time.

Oil coolers of the type under consideration have been so constructed that to remove the cores for inspection, cleaning or repair, it has 15 been necessary to disconnect the pipes by which the oil and the oil cooling fluid were conducted to and from the coolers and sometimes even to shift the coolers bodily to positions in which access could be obtained to the cores. When coolers are located in limited spaces, as they commonly are in submarine vessels, these operations entail much difficulty and work. It is another 20 object of this invention to provide an oil cooler from which the core may be quickly and easily 25 removed, even in a limited space, without moving the cooler or disconnecting the oil or oil cooling fluid pipes which are connected to it.

It is another object of this invention to provide an oil cooling unit which may be used alone, 30 if only a relatively small quantity of oil is to be cooled, or in conjunction with another similar unit or other similar units, if larger quantities of oil are to be cooled.

For a better understanding of the nature and 35 objects of this invention, reference is made to the accompanying specification wherein there are described the preferred embodiments of the invention which are illustrated in the accompanying drawings.

40 In the accompanying drawings.

Figure 1 is a top plan view, with parts broken away and in section, of an oil cooling unit in which this invention is embodied.

Figure 2 is a section taken on the line 2—2 of 45 Figure 1.

Figure 3 is a fragmentary section taken on the line 3—3 of Figure 1.

Figure 4 is a more or less diagrammatic side elevation of the oil cooling unit shown in the 50 preceding figures.

Figure 5 is a fragmentary section taken on the line 5—5 of Figure 2.

Figures 6 and 7 illustrate, more or less diagrammatically, alternative arrangements of a 55 plurality of the oil cooling units shown in the preceding figures.

Figure 8 is an end elevation, with parts broken away and in section, of a modified form of oil cooler.

50 Figure 9 is a side elevation, with parts broken

away and in section, of the oil cooler shown in Figure 8.

Figure 10 is a fragmentary section taken on the line 10—10 of Figure 8.

Each of the oil cooling units 19 which are illustrated in Figures 1 to 7 of the drawings includes a casing 20, preferably of cast bronze, which is adapted to rest on and be secured to a suitable foundation, and a cover 21, preferably of cast bronze, which is adapted to be secured to the 10 casing by studs and nuts 22 and 49.

In the opposite sides of the casing 20, adjacent one end, there are provided coaxially disposed oil outlet openings 23 which communicate with an oil passage 23a in the casing, and, adjacent the 15 other end, coaxially disposed oil intake openings 24 which communicate with an oil passage 24a in the casing. In the opposite sides of the casing, between the openings 23 and 24, there are provided coaxially disposed openings 25 which communicate with a large recess 25a in the casing between the passages 23a and 24a. It will be noted that the openings 23 and 24 are arranged symmetrically with respect to the openings 25 and the base of the casing 20 and that the openings 25 20 23, 24 and 25 are surrounded, respectively, by flanges 51, 52 and 53 to which pipes for conducting fluid into or from the unit 19 may be connected.

To the cover 21, in which there are provided oil 30 passages 23b and 24b which communicate, respectively, with the oil passages 23a and 24a in the casing 20, there is detachably connected by studs and nuts 26 a core unit 27 which, when the casing and the cover are assembled as shown in the 35 drawings, is located in the recess 25a. The core unit consists of a pair of oil headers 23c and 24c which communicate, respectively, with the oil passages 23b and 24b in the cover and into whose walls the studs 26 extend, and a core 28 located 40 between the headers. The core consists of a number of spaced tubes 33 which extend through and are connected to header plates 29 and reinforcing plates 30 and through which oil is adapted to flow from the header 24c to the header 23c. 45

The tubes 33 are preferably of the type disclosed in the Feldkamp Patent No. 1,055,324, issued March 11, 1913. The core is connected to the headers 23c and 24c by studs and nuts 31 which extend through the end flanges of the ribbed 50 spacers 32, the ends of the header plates 29 and into the walls of the headers. The spacers 32 serve to prevent endwise pressure sufficient to distort the tubes 33 being applied to them.

In the cover 21, there is provided a passage 34 55 which connects the passages 23b and 24b. With the passage 34, there is associated a valve housing 35 in which there is located a valve 36 which is urged to position to close the passage by a coil spring 37. The valve 36 normally prevents the 60

flow of oil through the passage 34, but when the pressure in the passage 24b exceeds a predetermined value, because of an obstruction in the core 28 or for any other reason, the valve opens against the resistance of the spring 31 and oil flows from the passage 24b to the passage 23b through the passage 34.

Between the contacting surfaces of the casing 20 and the cover 21 and the contacting surfaces 10 of the cover 21 and the core unit 27, there is interposed a gasket 38 which prevents oil and water escaping from the oil cooling unit and the leakage of oil into the water passage or water into the oil passages within the oil cooling unit. In the 15 lower surface of the cover 21, there are provided two grooves 39 of which each connects the several openings through which one group of the studs 26 pass and in the upper surface of each of the headers 23c and 24c, there is provided a groove 20 40 which connects the several openings for the studs 26 therein. In the lower surface of the cover 21, there are also provided two grooves 41 25 of which each connects, and extends beyond the outer of, the several openings through which one group of the studs 49 (which extend into the inner walls of the passages 23a and 24a) pass and in the upper surface of the inner wall of each of the 30 passages 23a and 24a, there is provided a groove 42 which connects, and extends beyond the outer of, the several openings for the studs 49 therein. Into each of the grooves 39 and 41, there extend from the upper surface of the cover 21 several bores 43 which pass through the gasket 38 into the corresponding grooves 40 and 42. The 35 grooves 39, 40, 41 and 42 and the bores 43 constitute a means of detecting and locating any leak in the joints between the water and oil passages in the oil cooling unit since if a leak occurs therein the leaking fluid will enter one of the grooves 40 43, 40, 41 and 42 and flow therefrom through the nearest of the bores 43 to the outer surface of the cover and from the position of the bore 43 in which the fluid appears and the nature of the fluid one can closely locate the position of the leak. 45 Oil to be cooled may be conducted into the unit 19 through either or both of the openings 24 and cooled oil may be conducted from the unit through either or both of the openings 23. If it is desired to conduct oil into or from the cooling 50 unit by only one opening, the opening which is not to be employed should be closed by a suitable cover plate. Water for cooling the oil passing through the unit may be introduced into the unit through either of the openings 25 and discharged therefrom through the other. To prevent the water by-passing the core during its 55 passage through the recess 25a, webs 50 are provided on the inner walls of the passages 23a and 24a and on the bottom of the casing 20. To 60 insure a uniform distribution of the water which passes through the core, a baffle or distributing plate 44 is secured to the core unit 27 on the side adjacent the opening 25 through which water is introduced into the recess 25a. 65 When an oil cooling unit 19 is operating under normal conditions, oil passes from the oil inlet opening or openings 24 to the oil outlet opening or openings 23, through the passage 24a, the passage 24b, the header 24c, the tubes 33, the 70 header 23c, the passage 23b and the passage 23a, as indicated by the solid arrows in Figure 2, and, during its passage through the tubes 33 is cooled by the water which flows therebetween in its passage from the water inlet opening 25 75 to the water outlet opening 25, as indicated by

the arrows in Figure 5. If, because of an obstruction in the core 28 or for any other reason, the resistance to the flow of oil through the core unit 27 exceeds a predetermined value, the pressure developed in the inlet end of the passage 5 34 will cause the valve 36 to open and oil will flow from the passage 24b to the passage 23b through the passage 34, as indicated by the dotted arrows in Figure 2.

The unit 19 may be made of relatively small 10 size and yet capable of cooling a large quantity of oil in a short time. When the nuts 22 and 49 are removed, the cover 21, together with the core unit 27, may be lifted bodily from the casing 20 for inspection, cleaning or repair, without 15 moving the casing or disconnecting any of the oil and water pipes which are connected to it.

It is apparent that each of the units 19 constitutes a complete oil cooler. However, if one of the units alone has not the desired oil cooling 20 capacity, two or more units may be used together. When two or more units are to be used together, they may be interconnected so that oil flows through their core units in parallel or in series.

In Figure 6, there are shown three oil cooling 25 units 19a, 19b and 19c so connected that oil flows through their core units 27, in parallel. In this installation, the three units are arranged so that their water openings 25 are coaxially aligned and that their oil inlet openings 24 and their oil outlet openings 23 are, respectively, on the same side of the water openings 25, with the juxtaposed flanges 51, 52 and 53 suitably connected and the "free" oil outlet opening 23 in the unit 19a and the "free" oil inlet opening 24 in the 35 unit 19c closed by cover plates 45 and 46 connected, respectively, to the flanges 51 and 52. Oil introduced into the "free" oil inlet opening 24 of the unit 19a will flow through the installation as indicated by the arrows, by-passing any 40 core unit 27 in which the resistance to the passage of oil exceeds a predetermined value. Water may be introduced into the installation through either of the "free" water openings 25 and will flow successively through the several recesses 45 25a.

In Figure 7, there are shown three oil cooling 50 units 19a, 19b and 19c so connected that oil flows through their core units 27 in series. In this installation, the three units are arranged so that 55 their water openings 25 are coaxially aligned and that the oil inlet openings 24 and the oil inlet openings 23 of the units 19a and 19c are located on the sides of the water openings 25 opposite that on which the corresponding oil openings of 55 the unit 19b are located, with the juxtaposed flanges 51, 52 and 53 suitably connected, the "free" oil outlet opening 23 of the unit 19a and the "free" oil inlet opening 24 of the unit 19c closed by cover plates 45 and 46 connected, respectively, with the flanges 51 and 52 and with imperforate "flow control plates" 47 and 48 interposed, respectively, between the juxtaposed flange 52 of the unit 19a and flange 51 of the unit 19c and between the juxtaposed flange 52 of the 65 unit 19b and flange 51 of the unit 19c. Oil introduced into the "free" oil inlet opening 24 of the unit 19a will flow through the installation as indicated by the arrows, by-passing any core unit 27 in which the resistance to the passage of oil 70 exceeds a predetermined value. Water may be introduced into the installation through either of the "free" water openings 25 and will flow successively through the several recesses 25a.

The oil cooler shown in Figures 8 to 10 of the 75

drawings consists of a cylindrical casing 60, preferably of cast bronze, provided with suitable supporting legs 61. The casing is closed at one end by an integral head through which extends a cooling water outlet opening 62 to which a water outlet pipe is adapted to be connected and at the other end by a head 63 which is detachably secured thereto by studs and nuts 65 and through which extends a cooling water inlet opening 64 to which a water supply pipe is adapted to be connected. Between the head 63 and the casing 60, there is interposed a baffle or distributing plate 93 which has the same function as the plate 44, hereinbefore referred to.

15 Within the casing 60, there is provided a core unit 66 which consists of a pair of oil headers 67 and 68 and a core 69 located between the headers. The core unit is supported by flanged cup-like brackets 70 and 71, which extend into the 20 interior of the casing through openings in the opposite sides thereof and are secured to the headers 67 and 68 by studs and nuts 72. The bracket 70 is secured to the casing by the studs and nuts 73 which secure the oil inlet fitting 86 thereto and the bracket 71 is secured to the casing by the studs and nuts 74 which secure the oil outlet fitting 87 thereto. The oil inlet fitting 86 is suitably designed for connection to an oil supply pipe and is connected with the interior 25 of the oil inlet header 67 by communicating openings 75 and 76 in the bracket 70 and the header. The oil outlet fitting 87 is suitably designed for connection to an oil discharge pipe and is connected with the interior of the oil outlet header 68 by communicating openings 77 and 30 78 in the bracket 71 and the header.

The core preferably consists of a number of spaced tubes 79 similar to the tubes 33, hereinbefore referred to, through which oil is adapted 40 to flow from the header 67 to the header 68. These tubes extend through and are connected to header plates 80 and reinforcing plates 81. The core is connected to the headers 67 and 68 by studs and nuts 82, which extend through 45 flanges on spacers 83, which have the same function as the spacers 32, hereinbefore referred to, the ends of the header plates 80 and into the walls of the headers. On the spacers 83, there are provided wings 84 which, in conjunction 50 with the ribs 85 on the interior of the casing 60, prevent water flowing from the water inlet opening 64 to the water outlet opening 62 from bypassing the core 69.

The oil inlet fitting 86 and the oil outlet fitting 87 are connected by a conduit 89 with which there is associated a valve housing 90 in which there is located a valve 91 which is urged to position to close the conduit by a spring 92. The valve 91 normally prevents the passage of oil 55 through the conduit 89, but when the pressure in the oil inlet fitting 86 exceeds a predetermined value, because of an obstruction in the core 69 or for any other reason, the valve opens against the resistance of the spring 92 and oil flows from 60 the inlet fitting 86 to the oil outlet fitting 87 through the conduit 89.

Under normal conditions, oil passes from the oil inlet fitting 86 to the oil outlet fitting 87 through the openings 75 and 76, the header 67 the 65 tubes 79, the header 68 and the openings 78 and 77 and is cooled during its passage through the tubes 79 by the water flowing therebetween in its

passage from the water inlet opening 64 of the water outlet opening 62. If, because of an obstruction in the core 69 or for any other reason, the resistance to the flow of oil through the core unit 66 exceeds a predetermined value, the pressure 5 developed in the inlet end of the conduit 89 will open the valve 91 against the resistance of the spring 92 and the oil will flow from the oil inlet fitting 86 to the oil outlet fitting 87 through the conduit 89.

10 The oil cooler illustrated in Figures 8 to 10, although compact and of relatively small size, is capable of cooling a large quantity of oil in a short time. To obtain access to the core 69, it is necessary only to remove the head 63 and the 15 baffle or distributing plate 93; and the core unit 66 may be removed from the casing through the opening thus uncovered after the brackets 70 and 71 have been disconnected from the core unit and the casing.

20 It will, of course, be understood that although the heat exchangers disclosed therein were designed primarily for use as oil coolers, they may be utilized for cooling or heating other liquids than oils.

25 I claim:

1. In a heat exchange unit, a casing a passage for one fluid which extends through the casing, two passages for another fluid which extend through the casing, and a passage connecting 30 the two second-mentioned passages, one of the first specified and last specified passages including an element which is located in the other and is capable of transmitting heat from the fluid in one to the fluid in the other of the first 35 specified and last specified passages.

2. In a heat exchanger, passages for two fluids, a wall between the two passages consisting of two parts, a groove in one of the juxtaposed surfaces of the two parts, and a plurality of spaced passages which extend at an angle to the groove 40 from the outer surface of one of the parts into the groove.

3. In a heat exchanger, a casing, an opening for one fluid extending through a wall of the casing, two openings for another fluid extending through the mentioned wall of the casing and located symmetrically with respect to the first-mentioned opening, and an opening for the first-mentioned fluid and two openings for the second-mentioned fluid extending through a wall of the casing other than that mentioned and arranged in the same positions with respect to each other as the openings in the first-mentioned wall.

4. In a heat exchanger, a casing, a cover for the 45 casing, a heat exchange element in the casing, a passage in which the heat exchange element is located extending through the casing and the cover, and a by-pass extending through the cover.

5. In a heat exchanger, a casing, a cover 60 removably secured to the casing, headers connected to the cover and extending into the casing, and a heat exchange element connected to the headers and located in the casing.

6. In a heat exchanger, passages for two fluids, a wall consisting of two parts between the two passages, openings for securing means in the two parts, a groove in one of the juxtaposed surfaces of the two parts connecting the mentioned openings, and passages extending from the groove to 70 the outer surface of one of the parts.

JOHN RALPH HOLMES.
